UNITED STATES PATENT OFFICE.

WILLIAM FORSYTH, OF BELVIDERE, ILLINOIS.

NEEDLE-BAR-GUIDING MECHANISM FOR SEWING-MACHINES.

SPECIFICATION forming part of Letters Patent No. 698,484, dated April 29, 1902.

Application filed November 8, 1901. Serial No. 81,550. (No model.)

To all whom it may concern.

Be it known that I, WILLIAM FORSYTH, a subject of the King of Great Britain, residing at Belvidere, in the county of Boone and 5 State of Illinois, have invented certain new and useful Improvements in Sewing - Machines, of which the following is a specification.

My invention relates to improvements in 10 sewing-machines, and has particular relation to the provision of a gib-race which can be adjustably regulated to coöperate with the cross-head or cam of the needle-bar.

The objects of my invention are to provide 15 a detachable gib-race which can be adjustably regulated.

A further object is to provide a gib which will coöperate with the race, and, further, to provide means for taking up the wear resulting from the reciprocating motion of the gib within the race.

To these and other ends said invention consists in the improved construction and combination of parts hereinafter fully described, 25 illustrated in the accompanying drawings, and particularly set forth in the appended claims.

In the drawings, Figure 1 is an elevation of the face-plate of a sewing-machine, showing the needle-bar in position and omitting 30 other parts which form no part of the invention. Fig. 2 is a sectional view taken on line 2 2 of Fig. 1. Fig. 3 is an enlarged plan view of the cross-head. Fig. 4 is an edge view of the same. Fig. 5 is a detail of the gib-race. 35 Fig. 6 is a detail of a modified form of gib connection with the cross-head.

In the provision of guides for the cross-heads of the needle-bar, so far as I am aware, it has heretofore been the practice to provide 40 a gib carried by the cross-head and adapted to coöperate with a fixed portion of the face-plate. By this construction there is the requirement of a careful forming of the parts primarily and afterward an accurate truing 45 of the guide or the gib, or both. Castings not perfectly made are therefore worthless, and hence there is an additional expense attached to the manufacture of this portion of the machine. In the present invention this requirement of a careful selection, &c., is eliminated 50 to a great extent in that the gib-race is not only detachable, but its position can be regu-

lated to correspond relatively to the proper position of the gib on the cross-head, it being necessary only that the openings for the 55 screws be tapped at the proper points. In the drawings I have presented a structure for accomplishing this result.

Referring thereto, 5 designates a face-plate of the usual form, guides for the gib, however, being omitted.

6 designates the needle-bar, and 7 the cross-head. The cross-head 7 is provided with the gib 8, either by its being formed integral therewith, as shown in Figs. 1 to 4, or by being secured thereto, as shown in Fig. 6. In the latter construction cams or cross-heads already in use can be utilized. As shown, the gib is preferably provided with means for taking up the wear, the means shown consisting in providing a slit 9, extending vertically therethrough, and an expanding-screw 10, operating therein, as best shown in Fig. 4.

The gib-race 11 consists of a plate of suitable material, having a slot 12, which forms 75 the raceway. Screw-holes 13 are provided at opposite ends, by means of which it may be secured to the face-plate. In securing the race in position the needle-bar, with the cross-head, is inserted, and its position is ascertained. The gib-race is also placed in position, after which the face-plate is tapped to receive the screws 14, which secure the race in its position. An oil-hole 15 is then tapped in the face-plate, which hole also serves to 85 permit access to the expanding-screw 10 to take up wear.

Inasmuch as the gib-race is detachable, it will be readily understood that its position relative to the cross-head can be regulated to 90 a nicety without the requirement of a perfect face-plate. Furthermore, the face-plate is provided with a minimum number of openings, in addition to which the race can be readily oiled and the wear taken up without 95 removal from the machine-head.

I do not limit myself to the precise details of construction, reserving the right to use modifications in so far as they may fall within the spirit and scope of the appended claims. 100

Having thus described my invention, what I claim as new is—

1. In a sewing-machine, the combination with the needle-bar; and the cross-head car-

ried thereby, said cross-head carrying a slitted adjustable gib; of a plate having a race for said gib detachably carried by the face-plate, said race-plate having means preventing a movement of the gib laterally.

2. In a sewing-machine, the combination with the needle-bar; and the cross-head carried thereby, said cross-head carrying a slitted adjustable gib; of a plate having a race for said gib detachably carried by the face-plate, said plate having a slot of a length to permit of the full longitudinal movement of the gib, whereby lateral movement of the gib will be prevented.

15 3. In a sewing-machine, the combination with a plate having a gib - race adapted to prevent lateral movement of the gib; of a cross-head having a slitted gib movable longitudinally of the race said gib having means constructed to expand the sides thereof for taking up wear.

4. In a sewing-machine, the combination with a plate having a gib - race adapted to prevent lateral movement of the gib; of a reciprocating cross - head carrying a gib, said gib having a slit; and an adjusting - screw carried by said gib and adapted to expand the sides of said gib to take up wear.

5. In a sewing-machine, a needle-bar; a cross-head carried thereby; a gib carried by the cross-head, said gib being slotted longitudinally; an adjusting-screw carried by the gib and adapted to expand the sides of the gib; and a plate having a gib-race detachably carried by the face-plate, said race extending on opposite sides of the gib.

In witness whereof I have hereunto set my hand in the presence of two witnesses.

WILLIAM FORSYTH.
